Primary Examiner—Caron D. Veynar*Assistant Examiner*—Sydney R Buffalow(74) *Attorney, Agent, or Firm*—Faegre & Benson LLP(57) **CLAIM**

The ornamental design for a product display, as shown and described.

DESCRIPTION

FIG. 1 is a perspective view of a product display.

FIG. 2 is a front view thereof.

FIG. 3 is a back view thereof.

FIG. 4 is a right end view thereof. A left end view thereof is an identical, mirror image of FIG. 3, and is omitted.

FIG. 5 is a top view thereof.

FIG. 6 is a bottom view thereof; and,

FIG. 7 is a perspective of FIG. 1 in an alternate position thereof.

In the drawings, the broken lines represent environmental structure forming no part of the claim.

1 Claim, 6 Drawing Sheets
